UNITED STATES PATENT OFFICE.

ELMER A. SPERRY, JR., OF BROOKLYN, NEW YORK.

DEPTH-CONTROLLED MINE.

1,415,614.

Specification of Letters Patent. Patented May 9, 1922.

Application filed April 16, 1917. Serial No. 162,245.

To all whom it may concern:

Be it known that I, ELMER A. SPERRY, Jr., a citizen of the United States of America, residing at 1505 Albemarle Road, Brooklyn, 5 in the county of Kings and State of New York, have invented certain new and useful Improvements in Depth-Controlled Mines, of which the following is a specification.

This invention relates to submarine mines, 10 more particularly to that class adapted to explode when a predetermined depth is attained.

One of the objects of this invention is to provide such a mine with a detachable buoy 15 or float, thus producing a practically unitary structure.

Another object is to provide a novel form of adjusting means for predetermining the distance between the mine and buoy, at 20 which the mine is to be exploded.

A further object is to provide means for preventing explosion of the mine while the above mentioned adjustment is being effected.

25 A still further object is to provide a novel form of adjusting tool.

Other objects and advantages will appear as the description of the invention proceeds.

Referring to the drawings which illustrate what I now consider the preferred form 30 of my invention:

Fig. 1 is a sectional elevation of the mine and buoy or float in normal, inoperative position.

35 Fig. 2 is a view illustrating the positions assumed by the parts after being launched.

Figs. 3, 4 and 5 are fragmentary sectional details illustrating the different positions of the firing and releasing mechanisms and Fig. 40 6 is an elevation of an adjusting tool.

My invention comprises a float or buoy, a mine or explosive container, firing mechanism, means for causing operation of the firing mechanism when a certain distance 45 between the float and buoy is attained and means for predetermining this distance.

The float or buoy may assume the form illustrated at 1 in Fig. 1. This float 1 is shown as being constructed of sheet metal 50 to form an annular airtight container 4, the inner wall 3 of the float being shown in the form of an inverted funnel. The bottom portion 5 of the float may be provided with an annular flange 6 adapted to be engaged

by fastening means, such as springs 7, 7, carried by the top 8 of the mine 2 thus forming a detachable or releasable connection between the mine and float.

The springs 7, 7 are of such strength that they will hold mine 2 and buoy 1 together 60 when these parts are dropping or thrown through the air, but which will permit separation of the above mentioned parts when launched, such separation being due to the weight of the mine.

65 The mine 2 is shown as a two part container, the central tubular portion containing a detonating charge 10 and the surrounding space containing a main charge 11.

The firing mechanism may take the form 70 of a plunger 12 and anvil 70. The latter is shown fixedly mounted within the tube 9 and as being in the form of an annulus, supporting at its inner portion a primer 14'. The plunger 12 is adapted to slide in a sleeve 75 13 and carries a firing pin 14 adapted to engage the primer. Suitable means are provided for holding the plunger in inoperative or non-firing position.

Such means may take the form illustrated 80 in Figs. 1, 3, 4 and 5 in which the plunger 12 is shown as provided with a plurality of pins 15 slidably radially with respect to the plunger and of such a length that when the outer ends engage the interior of the sleeve 13 the 85 inner ends extend into a recess 16 provided in the plunger 12. An internally threaded sleeve 17 also normally projects into said recess 16, the end which enters the recess being provided with an annular depression 18 in 90 which the pins 15 normally seat to secure the sleeve to the plunger. The opposite end of the sleeve 17 is provided with a flange 19 in engagement with a sleeve 20 suitably secured to the top 8 of the mine as by threaded engagement with a flanged member 21 riveted or otherwise secured to the said top 8. Thus as the sleeve 17 is held from downward movement, so also is the plunger 12 as long as these parts are secured to each other.

100 The sleeve 13 may be secured against longitudinal movement by screw threaded engagement with the interior of the fixed sleeve 20. Also while the weight of the plunger may be utilized to cause engagement 105 of the pin 14 and the primer, a spring 22 engaging the fixed sleeve 20 and the plunger may be provided to actuate the latter.

The releasing means is designed to release the plunger when a predetermined distance between the buoy 1 and mine 2 is reached and may take the form illustrated in the drawing and which is constructed as follows:

As has been previously stated the sleeve 17 is screw threaded on its interior and a screw 23 enters said interior portion. This screw 23 may be provided with an enlarged portion 24 adapted to be engaged by a shoulder 26 provided on the interior of a sleeve 25. As will later appear the release of the plunger 12 is effected by raising the latter. Means are therefore provided for raising the sleeve 25. For this purpose this last mentioned sleeve may be provided with a key-way 28 into which a screw 29 secured to a fixed housing 30 is adapted to project and the exterior of the said sleeve 25 may be screw-threaded. By virtue of the key-way and screw 29 the sleeve 25 is constrained to move only in a longitudinal direction so that if the nut 31, engaging this sleeve and capable only of rotative movement, is turned the sleeve 25 will be moved in a longitudinal direction. The above mentioned housing 30 is shown in the shape of a hollow cone adapted to fit into the funnel shaped portion 3 of the buoy and fixedly secured at its bottom to sleeve 20. A tube 32 may be provided at the top of the housing 30 which tube together with the fixed sleeve 20 prevents longitudinal movement of the nut 31. The means for rotating the nut 31 may assume the form of a reel 33 secured to said nut within the housing 30 and adapted to be rotated by a flexible member such as a cord or cable 34 wound around it. This cord or cable 34 is secured at its free end to the buoy 1 by any suitable means such as a link 35 secured to an eye 36 on the bottom 5 of said buoy. The cable 34 is shown as passing through an opening 37 in the housing 30 and may be passed through an opening 38 provided in a collar 39 fixed to the top of the housing 30 so that there will be no pull on the cable between the reel and buoy before the latter and the mine separate when launched and so that the mine will hang in a vertical position as it sinks through the water. Two of the springs 7 mounted on the mine, and designated as 7', 7'', may be arranged comparatively close together, one on either side of the eye 36 when the buoy and mine are in assembled position, (see Fig. 1) to prevent relative rotation of said last mentioned parts.

The reel 33 may be normally locked against rotation by means of a pin 40 adapted to pass through a bent-in portion 43 of housing 30 and into a socket member 41 secured to the reel. The socket entering end of the pin 40 may be annularly recessed 65 to be engaged by a spring 42 secured to the

socket member to prevent accidental derangement of the pin.

While the pin 40 could be withdrawn manually prior to the launching of the mine I refer to perform this function automatically. This function may be accomplished by securing the pin to the free end of the cable 34 in any suitable manner for example by means of a cord 44.

The embodiment of my invention illustrated in the drawings and described above lends itself readily to adjustment as to the distance between buoy and mine necessary to explode the latter. This adjusting means is designed to accomplish its adjusting function without in any manner disturbing or moving the firing plunger 12, in fact the latter is locked against movement of any kind, by virtue of the locking of the reel, until after the buoy is launched. 85

The above mentioned adjustment may be effected by locking the sleeve 17 against rotation and turning the screw 23. Bearing in mind that the adjustment is made with the reel locked, the sleeve 17 may be locked by providing a clutch connection 45 between it and the sleeve 25, this being the normal or inoperative position of the parts. Turning the screw 23 will, under these conditions, vary the distance between the shoulder 26 and the enlarged portion 24 of the screw so that the reel when released will have to make a larger or smaller number of revolutions, which means that a greater or smaller length of cable will have to be paid out to cause 100 release of the plunger 12. Springs 46 or other suitable means may be provided to prevent accidental derangement of the screw 23.

While the last mentioned element could be rotated by an ordinary screw driver, I prefer to use the form of adjusting tool shown in Fig. 6 and which may be constructed substantially as follows.

A shank 50 is provided at one end with a suitable projection 51, adapted to engage the head of the screw 23 to turn the same, and may be provided at its other end with suitable means for turning the tool, such as a handle 52. Means are provided on the tool for indicating at what depth the mine will 110 explode. Such means may take the form of a collar 54 slidable on the shank 50, of a smaller diameter than the inside diameter of the tube 32 and adapted to be locked in various positions along the shank. The locking means for the collar may take the form of notches 55 provided along one side of the shank and in any one of which a detent 56 carried by the collar is adapted to seat. This detent 56 is shown as mounted on a spring 125 57 secured at one end to the collar 54. A scale 53 is provided on the shank 50 which scale may be calibrated to read in depths at which the mine will explode. The adjustment is effected as follows: The collar is ad- 130

justed along the shank 50 until its top is coincident with the indication of the desired depth on the scale 53 and the detent will lock the collar in this position. The tool is then 5 inserted in the tube 32, engaged with head of the screw 23 and turned in the proper direction until the top of the collar 54 is flush with the top of tube 32.

In addition to the resilient securing means 10 7 between the mine 2 and buoy 1 additional securing means, such as a pin 60 passing through holes 61 in the tube 32, may be provided.

The advantages of the structure shown 15 and described up to this point will be apparent to those skilled in the art. Some of the important advantages are as follows: The whole device is in the form of a unitary structure adapted to be handled with comparative ease and safety, as the firing plunger is locked until the device is launched. The assembled device is of uniform diameter and all of the parts, including the cable attaching means, are within the outer confines 20 so that none of the parts are subject to accidental derangement or breaking off. The removable securing means at the top enables the device to be carried about and handled, prior to launching, without danger of separating the buoy and mine. By virtue of the 25 resilient middle joint between the buoy and mine the latter are held together when the device is launched but automatically separate when the device strikes the water. The funnel shaped concavity at the bottom of the buoy and the cone shaped housing 30 and tube 32 cooperate to provide for telescoping of the parts and to provide a satisfactory means for guiding the parts both in assembly 30 and in separation of the mine and buoy after launching.

The operation of my invention is substantially as follows: When it is desired to use one of the devices the pin 60 is removed and 45 the screw 23 is turned by means of the tool 50, which has previously been set for the required depth, until the top of the collar 54 is flush with the top of the tube 32. This part of the adjustment can be effected 50 in the dark as the operator can determine when the top of collar 54 is flush with the top of the tube 32 by the sense of touch. Furthermore, this part of the adjustment is effected without any necessity of lifting or 55 moving the mine. The adjustment of the collar 54 can be readily made as the tool 50 can easily be carried to a source of light or to any other suitable place. The adjustment having been made the device is then 60 ready for launching. The device is lifted, by taking hold of the mine 2, and thrown or placed overboard. When in the water the buoy 1 floats at the surface and the mine 2 starts to sink due to its weight. It 65 should be noticed that as the tube 32 is of

a length several times its diameter and as the length of cable between eye 36 and the pin 40 is greater than the length of said tube 32, all possibility of binding between the buoy 1 and mine 2 is avoided. After 70 the mine and buoy are separated the pin 40 is withdrawn so that the reel 33 is free to rotate. Further sinking of the mine causes the cable 34 to rotate the reel and consequently the nut 31 which causes the shoulder 75 26 to approach the enlarged portion 24 of the screw 23. The relative position of the mine and buoy at this stage of the operation is indicated in Fig. 2. The elevation of the nut 31 causes engagement between the shoulder 80 26 and enlarged portion 24 as indicated in Fig. 3. The further travel of the nut 31 due to the sinking of the mine now causes the elevation of the screw 23 and plunger 85 12 until the parts assume the position indicated in Fig. 4 in which position the pins 15 have passed above the top of sleeve 13 and are forced radially outward into the space above said sleeve due to the pressure of the spring 22, the weight of the plunger 90 12 and the co-acting bevelled faces of the said pins and the annular recess 18. The plunger 12 is now freed from the sleeve 17 and drops, by gravity or due to the propelling action of the spring 22, causing the 95 firing pin 14 to engage the primer 14', (as shown in Fig. 5) to explode the mine.

Viewed from a different standpoint, i. e., from the standpoint of convenience in manufacture and assembly it will be noticed that 100 my device is made up of three distinct units, the float or buoy 1, the explosive container or mine 2 and the firing mechanism containing housing 30 each of which parts can be separately constructed and all of which 105 parts can be readily attached for assembly. The housing 30 is secured to the container or mine 2 simply by screwing the sleeve 20 into the flanged member 21. The float 1 is then placed over the housing and snapped 110 into engagement with springs 7 and the pin 60 inserted through the tube 32. Furthermore it will be noticed that all of the securing means together with the mechanism are entirely within the outer cylindrical confines and near the longitudinal center line of the assembled device.

In accordance with the provisions of the patent statutes, I have herein described the principle of operation of my invention, together with the apparatus which I now consider to represent the best embodiment thereof, but I desire to have it understood that the apparatus shown is only illustrative and that the invention can be carried 120 out by other means. Also, while it is designed to use the various features and elements in the combination and relations described, some of these may be altered and others omitted without interfering with the 125 130

more general results outlined, and the invention extends to such use.

Having described my invention, what I claim and desire to secure by Letters Patent is:

1. In combination, a mine, means for exploding said mine at a predetermined depth below the surface of the water, adjusting mechanism for predetermining the depth at which said mine will be exploded and means for preventing the release of said exploding means while said adjustment is being effected.

2. In combination, a mine, a float, means for exploding said mine when said float and mine are spaced a predetermined distance, adjusting mechanism for determining the distance at which said mine will explode and means for preventing the release of said exploding means by actuation of said adjusting means.

3. In combination, a mine, a buoy normally in juxtaposition thereto and provided with a central opening, said mine being provided with a projecting portion adapted to enter said opening to serve as a guide in assembly and separation of the mine and buoy, a reel in said projected portion, a cable wound upon said reel and connected to said buoy and firing means controlled by said reel.

4. In combination, a mine, a buoy attached thereto, a detachable connection between said mine and buoy adapted to hold them together when dropping through the air but permitting automatic separation of said buoy and mine when launched and means controlled by the degree of said separation for causing the explosion of said mine.

5. In combination, a mine, a buoy attached thereto, a releasable connection between said mine and buoy whereby the former is supported by the latter when the latter is suspended, a second releasable connection between said mine and buoy adapted to hold them together when dropping through air, after said first releasable connection has been released, but permitting automatic separation of said buoy and mine when launched.

6. In combination, a mine, a buoy releasably attached in juxtaposition to said mine, firing mechanism for said mine adapted to fire the same upon separation of said buoy and mine, normally locked releasing mechanism for said firing mechanism and means for automatically unlocking said releasing mechanism when said mine and buoy are launched.

7. In combination, a mine, a float, firing mechanism for said mine, normally locked rotatable releasing mechanism for said firing mechanism, means for automatically unlocking said releasing mechanism when said

mine and float are launched and means for causing said releasing mechanism to release said firing mechanism when said mine and float are spaced a predetermined distance.

8. In combination, a mine, a buoy, firing mechanism for said mine, normally locked rotatable releasing mechanism for said firing mechanism, means for automatically unlocking said releasing mechanism when said mine and buoy are spaced a predetermined distance and means, including said releasing mechanism, for rendering said firing mechanism operative when said buoy and mine are spaced a distance apart different from the first mentioned distance.

9. In combination, a mine, firing mechanism therefor including a firing pin, means for retracting said firing pin to release it comprising a lost motion connection and means comprising a part of said mechanism for effecting an adjustment of the amount of lost motion.

10. In combination, a mine, firing mechanism therefor including a firing pin, means for releasing said firing pin comprising a lost motion connection, means comprising a part of said mechanism for effecting an adjustment of the amount of lost motion and means for preventing movement of said firing pin while adjustments are being made.

11. In combination, a mine, a buoy, said mine and buoy being normally in telescopic engagement and resilient means for maintaining said engagement when said mine and buoy are dropping through space and for preventing relative rotation of last named elements.

12. In combination, a mine, an element flexibly connected therewith, means including a rotatable element for exploding said mine and locking means for said rotatable element said locking means being connected to said flexible connection.

13. In combination, a mine, an element flexibly connected therewith, means including a rotatable element for exploding said mine when said mine and element are spaced a predetermined distance and means for preventing rotation of said rotatable element, said last named means being connected to said first named element.

14. In combination, a mine, an element, firing mechanism for said mine, normally locked releasing mechanism for said firing mechanism, means for automatically unlocking said releasing mechanism by separating said mine and element, and means for actuating said firing mechanism by further separation of said mine and element.

15. In combination, a mine, a buoy, firing mechanism for said mine, normally locked releasing mechanism for said firing mechanism, means for automatically unlocking said releasing mechanism by separating said

mine and buoy, and means for actuating said firing mechanism by further separation of said mine and buoy.

16. A two part mine, a releasable resilient connection between said parts, one of said parts being provided with a funnel-shaped recess, a funnel-shaped housing on the other of said parts adapted to seat within said recess; said parts being symmetrical in exterior appearance.

17. A two part mine, a releasable resilient connection between said parts, one of said parts being provided with a funnel-shaped recess, a funnel-shaped housing on the other of said parts adapted to seat within said recess, said parts being symmetrical in exterior appearance, and firing mechanism within said housing.

18. In a submarine mine, firing mechanism including a plunger, a member normally connected with said plunger to retract the same, means for disconnecting said plunger and member after said plunger has traveled a fixed distance, an element for actuating said member after said element has moved a certain distance relative to said mine, rotatable means for so moving said element and means for varying said last named distance, the first named distance remaining constant throughout.

19. In an explosive device, a plunger, a firing pin carried thereby, an extensible stem normally connected at one end to said plunger and carrying at its other end a head, a longitudinally movable sleeve provided with a shoulder for engaging said head and means for disconnecting said plunger and stem after said plunger has been retracted a certain distance, which distance is fixed and independent of the initial distance between said shoulder and head.

20. In a submarine mine, a plunger, a sleeve normally detachably connected at one end to said plunger, a flange on the opposite end of said sleeve, a fixed support between said flange and plunger for preventing movement of said plunger to firing position when said plunger is connected to said sleeve and means for disconnecting said sleeve and plunger by retraction of said sleeve.

21. In an explosive device, a plunger, a sleeve normally detachably connected at one end to said plunger, a flange on the opposite end of said sleeve, a fixed support between said flange and plunger for preventing movement of said plunger to firing position when said plunger is connected to said sleeve, a rod adjustably connected to said sleeve, a second sleeve, a lost motion connection between said second sleeve and said rod, means for moving said second sleeve and means for disconnecting said first mentioned sleeve and plunger after said plunger has moved a fixed distance.

22. In a submarine mine, a plunger, a sleeve normally detachably connected at one end to said plunger, a flange on the opposite end of said sleeve, a fixed support between said flange and plunger for preventing movement of said plunger to firing position when said plunger is connected to said sleeve, a second sleeve normally engaging said first sleeve at the opposite side of said flange to prevent movement of said plunger away from firing position, a lost motion connection between said sleeves, means for moving said second sleeve and means for disconnecting said first mentioned sleeve and plunger after said second sleeve has been moved a predetermined extent.

23. In a submarine mine, a plunger, a sleeve normally connected to said plunger to prevent movement of said plunger toward firing position, a second sleeve constrained to move in a longitudinal direction and normally in engagement with said first sleeve on the side opposite the plunger, a connection between said sleeves whereby rotation of said first sleeve is normally prevented, a nut restrained against longitudinal movement and in engagement with the exterior of said second sleeve and means for rotating said nut.

24. In a submarine mine, a plunger, a sleeve normally connected to said plunger to prevent movement of said plunger toward firing position, a second sleeve constrained to move in a longitudinal direction and normally in engagement with said first sleeve on the side opposite the plunger, a connection between said sleeves whereby rotation of said first sleeve is normally prevented, a nut restrained against longitudinal movement and in engagement with the exterior of said second sleeve, and means for rotating said nut, said means comprising a reel connected to said nut.

25. In a submarine mine, a plunger, a sleeve normally connected to said plunger to prevent movement of said plunger toward firing position, a second sleeve constrained to move in a longitudinal direction and normally in engagement with said first sleeve on the side opposite the plunger, a connection between said sleeves whereby rotation of said first sleeve is normally prevented, a rod screw-threadedly engaged with the interior of said first sleeve, an enlarged portion on said rod, a shoulder on said second sleeve adapted to engage said enlarged portion after a predetermined movement of said second sleeve and means for moving said second sleeve.

26. In a submarine mine, a plunger, a sleeve normally connected to said plunger to prevent movement of said plunger toward firing position, a second sleeve constrained to move in a longitudinal direction and normally in engagement with said first sleeve

6

on the side opposite the plunger, a connection between said sleeves whereby rotation of said first sleeve is normally prevented, a rod screw-threadedly engaged with the interior of said first sleeve, an enlarged portion on said rod, a shoulder on said second sleeve adapted to engage said enlarged portion after a predetermined movement of said second sleeve and means for moving said second sleeve, said means comprising a nut in screw-threaded engagement with said second sleeve and a reel connected to said nut.

27. In a submarine mine, firing mechanism, means comprising a reel for rendering said firing mechanism effective, a cone shaped housing for enclosing said reel, a cable on said reel, an eye member near the apex of said cone, said cable passing from said reel, through an opening in said housing and then through said eye member and means for locking said reel to said housing, said last mentioned means comprising a pin connected to said cable.

28. A submarine mine comprising a float, a firing mechanism containing housing and an explosive container, an automatically detachable connection between said float and container and a detachable connection between said housing and float.

29. In combination, an explosive container, a firing mechanism containing housing detachably secured to said container and projecting therefrom, a float provided with a central recess extending therethrough adapted to receive and enclose said housing and removable means for the top of said housing whereby said housing may be supported from said float.

30. The combination of a casing, a firing mechanism therein including an axially

movable member and a reel having coacting threads whereby rotation of the reel causes axial movement of said member for firing, a flexible member wound on the reel and connected thereto, and a lock for holding the reel against movement secured to the flexible member so as to be released thereby; substantially as described. 45

31. The combination of a casing and a firing mechanism therein consisting of a spring actuated firing pin, an interiorly threaded axially movable member for actuating the pin, a headed rod having threaded engagement with said member, a hollow exteriorly threaded shaft within which the headed rod lies and which is provided with a shoulder to engage the head of the rod, means for holding the hollow shaft against rotational movement and permitting axial movement thereof, a reel having internal threads coacting with the external threads on the hollow shaft, and a flexible cable wound on the reel and connected thereto; substantially as described. 50

32. In combination, a mine, a buoy, firing mechanism including a plunger, a member normally connected with said plunger to retract the same, means for disconnecting said plunger and member after said plunger has traveled a fixed distance, an element for 70 actuating said member after said element has moved a certain distance relative to said mine, means for so moving said element connected with said buoy, and means for varying said last named distance, the first named 75 distance remaining constant.

In testimony whereof I have affixed my signature.

ELMER A. SPERRY, JR.
